VOLTAGE REGULATOR

Wilford L. Stevens, Vancouver, British Columbia,
Canada

Application October 20, 1936, Serial No. 106,688

3 Claims. (Cl. 200—111)

This invention relates to a voltage regulator or controller and has for its specific object the automatic regulation of voltage as generated by an electrical dynamo.

Other objects of my invention are to provide an automatic voltage regulator or controller for electrical generators which shall be small and compact, of simple construction and rugged design, and able to maintain close regulation of voltage and be highly responsive and quick acting.

My invention has been designed more especially for use with alternating current generators of the smaller sizes whose inherent regulation is generally very poor as, whenever load is added to such generators, their voltage usually falls and fluctuates rapidly, causing lights receiving electrical energy from such generators to flicker and in some cases to burn very dimly, and it is one of the objects of my invention to obviate the fluctuation of voltage of such generators by the use of the device I have perfected.

My invention is further designed to take care of the worst conditions of voltage drop that are caused by the sudden application of inductive loads such as the switching on of ordinary induction motors, and my device is designed to immediately compensate for these suddenly applied load changes in a simple and efficient manner by certain inherent characteristics which are solely due to the special combination and assembly of several well-known pieces of apparatus which are so co-ordinated together to produce the results desired.

The complete apparatus presents many improvements, both in structure and performance, over other forms of apparatus designed to produce somewhat similar results.

My invention and the nature of same will be more readily understood by reference to the following specification and accompanying drawings forming part of this application, and in which—

Figure 1 is a front elevation of panel board upon which voltage regulator is mounted.

Figure 2 is a side elevation of panel board mounted upon the end of a small motor that actuates the moving parts of the voltage regulator.

Figure 3 is a schematic diagram of electrical circuits of voltage regulator.

Figure 4 is a diagrammatic illustration of time duration per revolution of eccentric that contacts 18 and 19 are engaged to control voltage, viz:

A illustrates time duration of engagement of contacts 18 and 19 for light load position.

B illustrates time duration of engagement of contacts 18 and 19 for medium load position.

C illustrates time duration of engagement of contacts 18 and 19 for full load position.

In the drawing, which illustrates a preferred construction, like numerals indicate like parts and the numeral 1 indicates a constant speed motor of approximately 900 R. P. M. preferred speed having a non-conducting panel board 2 mounted upon the end frame of the motor.

Upon the face side of the panel board are mounted the various elements comprising the voltage regulator and the numeral 3 indicates an apertured and vented casing or housing containing a sensitive voltage solenoid 4 having a movable core 5 so mounted in the centre that it rises and falls with variations of voltage.

To the top of the core 5 is mounted a threaded rod 6 which is co-operatively engaged by one end of a pivotable mounted spring bar 7. The rod 6 is adjustably mounted upon the end of the spring bar 7 by reason of a pair of helical compression springs 8 mounted upon the rod 6 above and below the spring bar 7 and having adjusting nuts 9 acting upon the helical compression springs whereby the end of the spring bar 7 is flexibly tensioned and secured therebetween.

The upper end of the rod 6 is further suspended by a helical suspension spring 10 that is adjustable through an adjusting screw 11 mounted in the outer end of a supporting arm 12 secured upon the face of the panel board 2 adjacent the top.

The lower end of the movable core 5 is connected to a dashpot rod 13 projecting through the bottom of the solenoid casing 3 and terminating in the dashpot 14 mounted below the bottom of the solenoid casing 3. The solenoid 4 is connected to terminals 15 mounted upon the face of the panel board and having connections on the back thereof.

The inner end of the spring bar 7 is rigidly secured to a pivotable square block 16 mounted upon the face of the panel board and upon the opposite side of the square block 16 is secured another spring bar 17 which carries an adjustable contact point 18 upon the outer end.

The contact point 18 engages with another movable contact point 19 likewise mounted upon the end of another spring bar 20 mounted below the spring bar 17. The inner end of the spring bar 20 is also rigidly secured to a square mount-

ing block 21 firmly mounted upon the face of the panel board.

The spring bar 20 is reinforced by an auxiliary flat spring 22 suitably mounted upon the face 5 of the panel board below the spring bar 20.

Mounted upon the spring bar 20 intermediately of the square mounting block 21 and contact 19 is a fibre wearing piece 23 suitably fastened to spring bar 20 which engages with a cam or eccentric 24 mounted upon the end of the motor shaft 25 that projects through the front of the panel board 2 and imparts movement to the spring bar 20 whenever the motor operates.

The contact 19 is also provided with an independent up-and-down movement upon the end of the spring bar 20 through being mounted within a vertical cylindrical container or cylinder 26 secured upon the end of the spring bar 20.

The contact 19 extends and projects through the bottom of the cylinder 26 and is engaged by a light spring 27 mounted below the lower side of the spring bar 20.

The lower or bottom end of the contact 19 is connected to a flexible pig-tail connection 28 mounted upon the face of the panel board and having a connection at the back of the board.

Conveniently placed upon the face of the panel board is a control rheostat 29 that is connected in series with the sensitive voltage solenoid 4.

Adjacent the bottom of the panel board are three knife switches 30 that are connected with the solenoid, motor and regulator contact circuits.

The above description is comprehensive of a preferred form of construction of the voltage regulator and below is given the theory of operation.

In the schematic wiring diagram of electrical circuits shown in Figure 3, the part above the dot and dash line represents the circuits of a conventional A. C. generator with the exciter and the usual rheostats.

To regulate the voltage by hand we may cut in or out resistance at either or both rheostats 31 or 32. We shall concern ourselves only with rheostat 32 assuming that rheostat 31 is in its best operating position.

Now with 32 in the "all in" position, we have a minimum voltage condition of our generator 33 and exciter 34. If we connect a telegraph key across to the rheostat 32, we may bring the voltage up to normal by operating the "key" to short out 32. When normal voltage is reached we open the key, thus allowing the voltage to fall somewhat. By rapidly manipulating the key, we can maintain normal operating voltage under all conditions 55 of load.

In the voltage regulator we replace the key by the rapidly revolving eccentric 24 and contacts 18 and 19. This, however, will only give us a steady voltage at 33 for one value of load. Should 60 the load change, the voltage at 33 will change. Now, as the load increases, we can obtain steady voltage at 33 by depressing contact 18, thus causing 18 and 19 to make contact for a greater part of each revolution of the eccentric or cam 24 and 65 increasing the exciter voltage 34.

At the maximum load condition, 18 and 19 will make contact during the whole of each revolution of eccentric 24, and at minimum load condition, will make contact for a very small part of 70 each revolution or may remain entirely apart.

Instead of operating contact 18 manually, we operate it by suitable mechanical connections to the movable core 5 of the sensitive voltage solenoid 4.

75 An increase of load of the main generator 33

causes the core 5 of the solenoid to rise slightly, thus increasing the time duration of contacts 18 and 19. Regulation of voltage within 1% of normal can be maintained with this regulator, and very suddenly applied loads of induction motors 5 do not disturb the generator voltage appreciably.

Duration of contact per revolution is shown diagrammatically at Figure 4 for various generator loads. The amount of contact per revolution is represented by the position of the eccentric above 10 the dotted line. Compounding, or providing a rising voltage characteristic with increase of load to compensate for line drop where it is necessary, is afforded by means of a booster circuit which consists of a coil 35 connected in reverse or differentially, and wound on the same core as solenoid 4.

This is connected in series with the secondary of a standard current transformer 36 connected into one leg of the same circuit as the potential 20 or sensitive voltage solenoid. To adjust the amount of boosting, a suitable adjustable rheostat 37 is connected in parallel with the current transformer.

With this resistance all-in circuit, the boosting 25 effect is at maximum, and with the resistance all-out or the current transformer secondary short-circuited, the boosting effect is minimum.

To regulate voltage on larger machines, two or more contacts are mounted on contact bars 30 17 and 20, and connected to divide the rheostat current between them to prevent undue arcing of these contacts, or a suitable system of relays may be employed to handle these large currents.

As shown in the drawing, the regulator is 35 mounted upon the face of a suitable non-conducting panel 2 which in in turn is fastened by suitable brackets directly to the frame of the driving motor 1.

The windings of the solenoid 4 and motor 1 40 are connected across the mains of the generator 33 whose voltage is to be regulated, either directly, in the case of low voltage generators, or through potential reducing transformers in the case of high potential generators. 45

A condenser of suitable value is shunted across contacts 18 and 19 to prevent undue arcing. By manipulation of rheostat 29 which is connected in series with the winding of the sensitive voltage solenoid 4, adjustment of the main line voltage 50 is secured.

Having now described my invention and the nature of same, what I claim and desire to be protected in, by Letters Patent, is:

1. In an electric voltage regulator, a panel base, a solenoid mounted vertically on said base, a core within the solenoid and having projections beyond both ends of the core, a vibration damper connected to the lower core projection, a suspension spring to which the upper core projection is secured, said upper core projection including a threaded rod, a pair of balance springs and a pair of adjusting nuts on said rod, a pivoted member including a spring bar one end of which engages said upper core projection between said balancing springs, said pivoted member also including a vibrating spring bar having a contact point, a second vibrating spring bar also having a contact point to cooperate with the first mentioned contact point, a continuously rotating cam 70 located between said vibrating bars for effecting vibration thereof, and means continuously tending to close said contact points together.

2. In a voltage regulator for controlling fluctuation of voltage of an A. C. generator, a panel, a 75

- 5 rotary motor mounted on said panel, a cam on the shaft of said motor, a solenoid mounted on said base, a core in said solenoid, a dashpot connected to said core to dampen its movements, a suspension spring for said core, a member pivoted to said panel and comprising two spring arms each having a free end, means connecting the free end of one of said arms resiliently with said core, a contact point carried by the free end 10
10 of the other of said arms, a third spring arm beneath said cam and operatively engaged thereby, means rigidly mounting one end of said third arm on said panel and said third arm having a free end on which is mounted a contact point to 15 cooperate with the first mentioned contact point, and a spring engaging said third arm and continuously tending to press it toward said cam, all being arranged substantially as and for the purposes described.
- 15 20 3. In a voltage regulator for controlling fluctuation of voltage of an A. C. generator, a panel, a rotary motor mounted on said panel, a cam on the shaft of said motor, a solenoid mounted on said base, a core in said solenoid, a dashpot connected to said core to dampen its
25
- movements, a suspension spring for said core, a member pivoted to said panel and comprising two spring arms each having a free end, means connecting the free end of one of said arms resiliently with said core, a contact point carried by 5
- 10 the free end of the other of said arms, a third spring arm beneath said cam and operatively engaged thereby, means rigidly mounting one end of said third arm on said panel and said third arm having a free end on which is mounted a contact point to cooperate with the first mentioned contact point, and a spring engaging said third arm and continuously tending to press it toward said cam, a tubular socket fixed to said third arm in which socket said last named contact point is 15 located and through the bottom of which the same contact projects, a flexible conductor one end of which is mounted on said panel and the other end of which is secured to the projecting end of the third arm's contact, and a spring carried by said third arm for engaging said third arm's contact to urge it in a direction toward the first mentioned contact.
- 20
